ARMCHAIR

Roy A. Cramer, Kansas City, Mo.

Application October 18, 1950, Serial No. 12,626

Term of patent 14 years

(Cl. D15—1)

To all whom it may concern:

Be it known that I, Roy A. Cramer, a citizen of the United States, residing at Kansas City, in the county of Jackson and State of Missouri, have invented a new, original, and ornamental Design for an Armchair, of which the following is a specification, reference being had to the accompanying drawing, forming part hereof.

In the drawing:

Fig. 1 is a perspective view of an armchair showing my new design.

Fig. 2 is a front elevational view thereof.

Fig. 3 is a section taken on line 3—3 of Fig. 1.

Fig. 4 is a section taken on line 4—4 of Fig. 1.

Fig. 5 is a section taken on line 5—5 of Fig. 1.

The dominant features of the design are shown in full lines in the drawing.

I claim:

The ornamental design for an armchair, as shown and described.

ROY A. CRAMER.
